UNITED STATES PATENT OFFICE.

ALBERT M. FREISE, OF SAN FRANCISCO, CALIFORNIA.

WALL-SEAT.

1,199,002.

Specification of Letters Patent. Patented Sept. 19, 1916.

Application filed November 5, 1915. Serial No. 59,797.

To all whom it may concern:

Be it known that I, ALBERT M. FREISE, a citizen of the United States, residing at San Francisco, in the county of San Francisco and State of California, have invented certain new and useful Improvements in Wall-Seats, of which the following is a specification.

This invention relates to improvements in that type of foldable wall seats disclosed in my previous patent for wall seat, No. 1,182,004, granted March 16, 1915, the object of the present device, however, being to provide a simpler and, therefore, more easily and cheaply manufactured article.

While the foregoing is one of the main features of this device, from a structural standpoint the essence of my invention lies in the peculiar connections intermediate the seat member and its coöperating back element and those intermediate the latter and its support such that, firstly, a quick or ready disengagement of the first mentioned connections is possible, for the purposes hereinafter to be more fully explained, and that, secondly, the back will have imparted to it a movement into the housing provided for the seat construction and into an inoperative position lying directly adjacent to the seat element aforesaid.

A still further object is to provide means which in one direction of movement of the seat positively actuates the back to direct it into proper operative position and which in the other direction of movement guides said back into its inoperative position.

These and such other objects as may hereinafter appear are attained by the novel construction, combination, and arrangement of parts to be hereinafter specifically described and claimed.

Reference will now be had to the accompanying drawings forming a part of this specification, wherein:

45 Figure 1 is a perspective view showing an embodiment of my invention in unfolded operative position. Fig. 2 is a vertical sectional view showing the seat in folded or closed position. Fig. 3 is a similar sectional view showing the seat in open operative position and in dotted lines the position into which the back member may be raised for access to the interior of the seat casing and rear of the seat. Fig. 4 is a vertical sectional view with the seat sections in a partially raised position, preliminary to fold-

ing into the casing, showing particularly the coöperation with the guide means for directing rearward and forward movement of the back section of the seat. Fig. 5 is a front elevation of the wall seat in closed condition. Fig. 6 is a perspective view of a connecting member for connecting the back section to the seat section; and Fig. 7 is a perspective view of the link connection intermediate the back section and its support.

Throughout the following detail description, and on the several figures of the drawings, similar parts are referred to by like reference characters.

The subject matter of this invention, as will readily be understood by those skilled in the art to which said invention refers is susceptible of being constructed as a unit or distinct device capable of application to walls or other similar supports by exterior or interior attachment as may be desired. In its preferred embodiment which is disclosed in the drawing it is a unitary structure but it is within the purview of this invention that the casing element may be dispensed with and the foldable seat members, together with their coöperative elements applied to a wall by inserting in said wall and attaching the parts to the wall studding or plaster surfaces. However, the numeral 1 designates a casing for housing the seat members hereinafter more particularly described, said casing being provided with the face frame pieces 2, 3, and 4, 4. This casing is designed to be inserted into a wall and fastened between the studding thereof in any well known manner, and as particularly shown in Figs. 1 and 2 of the drawing. To the lower cross piece 3 is pivotally connected a seat member or section 5 hinged adjacent to its inner end as at 6, said seat section being of a size corresponding to the front opening of the casing 1 and constituting, 100 as in my previous patent, a closure for said opening when the seat is in its closed inoperative position. The seat member 5 is adapted to be swung in a vertical plane and when swung downwardly its rear extremity 105 coacts with an inner horizontally disposed cross piece 7 which forms the main support for sustaining weight as when a person is seated upon the seat member. To the rear portion of the seat section 5 is attached a 110 cross piece or cleat 8 which is designed primarily to prevent the seat section from split-

ting under undue strain, or warping, and this cleat is further utilized to hold the connecting members 9 to the seat section, one of said connecting members being distinctly shown in Fig. 6 of the drawing to consist of a base or lateral flange 10 and the upstanding body portion 11. The flange 10 of each of these members is secured to the inner face of the seat section 5 by fastening members extending through the flange 10 and said connecting member is further secured to the cleat 8 at its ends by means of the fastening members 17 so that a rigid connecting means constituting substantially a hinged member is provided for the folding seat construction and one which is susceptible of holding the strain which may be placed upon it as hereinafter pointed out. Coöoperating with the seat section 5 is a back section 12 which is operatively connected to the seat section 5 for actuation thereby in the opening or closing of the foldable seat construction. This back section is provided at its lower lateral edges with projecting headed studs 13 adapted normally to be disposed in open slots 14 formed in the connecting members 9. It will be observed by reference particularly to Fig. 6 that the slot of each of the connecting members 9 is tortuous in formation and the studs under normal conditions are seated at the closed extremities of said slots. The upper end of the back section 12 has attached thereto a cleat or cross piece 15 which acts as a spacing member, to bring back section 12 out past casing frame 2 whereby leaning against frame is eliminated and to it is attached a second cross piece 16. This latter cross piece has pivotally connected thereto at each side a slotted link 17 which link is in turn attached to the side walls of the casing 1 by means of fastening members such as screws 18 projecting into the slots 17 of the links 17. The peculiar connecting member, most distinctly shown in Fig. 7 of the drawing is an important feature of this invention because it performs a peculiar function in directing the movements of the upper extremity of the back section under the actuation of the seat section 5 in a manner to be later distinctly described. The upper edge of the cross piece 16 carrying the link 17 is formed with a rearward projection or a beveled surface as indicated at 19 which surface in the operation of folding or unfolding of the seat or closing and opening movement thereof is adapted to cooperate with a projection or cam 20 attached to the rear wall of the casing 1. In one movement of the seat member this cam aforesaid imparts sudden forward movement to the back section for the purpose of insuring the movement of said back section in the proper direction and preventing the likelihood of the link connection 17 stepping on dead center

or with its pivot members in such alignment as would preclude the full opening of the seat into its downward swung position shown in Fig. 3. It will be observed from this figure that the back section 12 is of such size and dimension as to substantially close the opening of the casing when the said section 5 is opened or in its downward swung position and this is a desirable feature inasmuch as it hides the operating members 75 of the seat elements disposed within the casing from view.

Describing the operation of this device and the particular movements of its elements, when opening the seat, the operator 80 grasps the handle 21 on the upper extremity of the seat section 5 and pulling downwardly causes the back section 12 to rise slightly as permitted by the slotted link connections 17 until the lower extremity of the 85 back section passes outwardly of the opening of the casing whereupon the back section begins to descend, and as it falls the link connections 17 move downwardly with the back until the projections or studs 18 approach the upper extremity of the slots 17 at which time the cross piece 19 of the back section impinges the cam member 20 lying in its path of downward movement, imparting positive forward movement outward of 90 the casing to the upper end of the back section throwing the links over the studs 18 until as the seat section 5 reaches its lowermost position, the upper end of the back or more strictly the cross piece 19, abuts against 95 the frame piece 2 of the casing. In this position it will be understood the back member is wedged in place by the link members 17, as shown most clearly in Fig. 3 of the drawing and the arrangement is such that 100 this cross piece 19 sustains a portion of the weight of the person on the seat, in coöperation with the support afforded by the cross piece 7 with which the rear end of said seat section contacts as hereinbefore described. 105 The wedging action above referred to affords a distinct advantage in that should the seat section be accidentally dropped in opening the device, the position of the back member, as above described, will prevent the 110 seat from bouncing when the rear end of said seat section contacts with its stop member 7. Upon raising the seat section, the reverse of the foregoing movement takes place, it being particularly observed from 115 Fig. 4 of the drawing that at a certain point in the closing action the back section 12 is brought into coöperation with the cam member 20 which directs said back section upwardly within the casing and precludes the 120 upper end of the back section from contact with the back at such an angle as to prevent the complete closing of the seat elements. Therefore, the cam performs the dual function of a guide in this closing operation. As 125 130

a matter of fact the cam member 20 is a controlling element for the link members 17 inasmuch as it imparts positive movement of the back section as provided for by said 5 link connections. Another special feature of this construction is the readiness with which the back member may be detached from the seat section 5. Under some conditions it is desirable to obtain access to the interior of 10 the casing 1 either for the purpose of painting the rear end of the seat and the inner walls or for the purpose of access to the connections for the back member, under which conditions it is only necessary to disengage 15 the projections 13 of the lower end of the back section 12 from the slots 14 of the connecting members 9 whereupon the lower end of the back section may be raised to a position shown in dotted lines in Fig. 3. This 20 freedom of movement or disconnection of the lower end of the back section from the seat section permits the upper end of the back section to drop downwardly as permitted by the slotted links 17 and then the 25 back section may be entirely withdrawn from the casing 1 by outward movement of the back section.

It will be obvious that the seat section will 30 assume its complete closed position and maintain such position when and as long as the weight of the back section parts is rearward of the hinge connections 6, and likewise the parts will assume their open position automatically when the weight is 35 brought forward of the hinge connection just mentioned.

It will be apparent from the foregoing 40 description that a very simple one-operation seat of a foldable character is provided and one which may be readily manufactured cheaply where such construction may be desired.

It will be understood, of course, that 45 slight changes in the details of construction and arrangement of parts may be made within the spirit of the invention and within the scope of the appended claims.

Having thus described my invention, what I claim as new is:

50 1. A foldable seat of the class described comprising, in combination, a support, a seat section pivotally attached thereto, a back section operatively connected to the seat section, a shiftable connection intermediate the back section and the support, stop means for limiting movement of the seat section and sustaining the same when in its downward swung position, and stop means carried by the support and adapted to be impinged by the upper portion of the back section to limit forward movement of the same and to prevent bouncing of the seat when the latter is dropped into contact 55 with its stop means aforesaid.

60 2. A foldable seat of the class described

comprising, in combination, a support, a seat section pivotally attached thereto, a back section operatively connected to the seat section at one end, a connection intermediate the other end of the back section 70 and the support for directing movement of said back section under actuation of the seat section, and means on the support adapted to cooperate with the back section for controlling action of the connection aforesaid. 75

3. A foldable seat of the class described comprising, in combination, a support, a seat section attached thereto and arranged to swing in a vertical plane, a back section operatively connected to the seat section for 80 actuation thereby, and a contact member on the support with which the back section impinges for directing said section into operative position.

4. A foldable seat of the class described 85 comprising, in combination, a support, a seat section attached thereto and arranged to swing in a vertical plane, a back section operatively connected to the seat section for actuation thereby, and a guide member on 90 the support adjacent to the back section arranged to engage the latter when the seat is swung into inoperative position for directing the back section into its relative 95 inoperative position.

5. A foldable seat of the class described comprising, in combination, a support, a seat section attached thereto and arranged to swing in a vertical plane, a back section operatively connected to the seat section for 100 actuation thereby, and a cam member disposed in the path of movement of the back section for positively throwing the back into operative position when the seat is 105 swung in one direction and for guiding the back section into inoperative position when the seat is swung in the opposite direction.

6. A foldable seat of the class described comprising, in combination, a casing, a seat section hingedly connected to the casing at 110 an intermediate point in the length of said section, a rear extension on the seat projecting into the casing, a back section pivotally connected to the seat section intermediate the length of the latter, link members pivotally connected to the top portion of the back section and similarly connected to the casing to cause forward and rearward movement of the back section under actuation by the seat section, and stop means on the 115 casing adapted to be impinged by the rear extension of the seat section for limiting its movement.

7. A foldable seat of the class described comprising, in combination, a support, a seat section pivotally attached thereto, a back section operatively connected at one 125 end to the seat section for actuation thereby, a link member pivotally connected to the other end of the seat section and to the 130

- support for directing rearward movement of the back section, and means associated with the back section for preventing the link from stopping on dead center.
5. 8. A foldable seat of the class described comprising, in combination, a support; a seat section pivotally attached thereto, a back section operatively connected at one end to the seat section for actuation thereby;
- 10 by a link member pivotally connected to the other end of the seat section and to the support for directing rearward movement of the back section, and means on the support for shifting the back section forwardly
- 15 on the pivot connection of the link with the support during downward movement of the seat section.
9. A foldable seat of the class described comprising, in combination, a support, a seat section pivotally attached thereto, a back section operatively connected at one end to the seat section for actuation thereby, a link member pivotally connected to the other end of the seat section and to the support for directing rearward movement of the back section, means on the support for shifting the back section forwardly on the pivot connection of the link with the support during downward movement of the seat section, and stop means for limiting movement of the back section.
10. A foldable seat of the class described comprising, in combination a casing, a seat member pivotally attached to the casing, a back member movable into the casing and connected to the seat member for actuation thereby, and connecting means intermediate the upper end of the back member and the casing for directing said end inwardly or outwardly of the casing, said connecting means being shiftably connected with the casing to permit movement of said means with the back member.
11. A foldable seat of the class described comprising, in combination, a casing, a seat member pivotally attached to the casing, a back member movable into the casing and connected to the seat member for actuation thereby, a slotted link pivotally connected to the upper portion of the back member, and pivot means on the casing engaging into the slot of said link.
12. A foldable seat of the class described comprising, in combination, a casing, a seat member pivotally attached to the casing, a back section movable into the casing and connected to the seat member for actuation thereby, a slotted link pivotally connected to the upper portion of the back section, and pivot means on the casing engaging into the slot of said link.
13. In a foldable seat of the class described, a seat section adapted to swing into extended operative and closed inoperative positions, a back section operatively connected therewith at one end, and means whereby the connection for said end may be temporarily "broken" to permit the back to be raised away from the seat.
14. In a foldable seat of the class described, a seat section adapted to swing into extended operative and closed inoperative positions, a back section operatively connected therewith at one end, connecting means carried by one of said members, and means on the other member removably interlocking with the connecting means.
15. In a foldable seat of the class described, a seat section adapted to swing into extended operative and closed inoperative positions, a back section operatively connected therewith at one end, a connecting member attached to one of said members and having an open slot, and pivot means on the other of said members engageable in the slot aforesaid to operatively connect the back and seat sections together.
16. In a foldable seat of the class described, the combination of a casing, a seat section pivotally connected thereto, a back section connected to the casing and arranged interiorly thereof, and means detachably connecting the other end of the back section to the seat section whereby to permit raising of the back section and movement of said section outwardly of the casing for access to the interior of the casing.
17. A wall seat of the class described comprising in combination a casing, a seat member pivotally connected therewith, a back member operably connected to the seat for movement into and out of the casing incidental to movement of the seat, and stop means carried by the back limiting outward movement of the back and permitting said back to be entirely projected from the casing.
- In testimony whereof I affix my signature.

ALBERT M. FREISE.
